COUPLER

Edwin P. Sundholm, Albert City, Iowa

Application March 21, 1941, Serial No. 384,463

3 Claims. (Cl. 285—169)

The present invention relates to a certain new and useful multi-jawed hydraulic snap-on chuck-type coupler for use in connecting the discharge hose or conduit of a grease-gun or lubricant-dispensing device or pump onto a headed lubricant-receiving "fitting" or "nipple."

One of the objects of the present invention is to increase the efficiency of the coupler and to facilitate and enhance its various functions in gripping and sealing against the "fitting" and in quickly releasing the fitting when release is desired.

With the above and other objects in view, the present invention consists of certain novel features and details of construction all of which will appear more fully from the following description and accompanying drawings.

For the purpose of illustrating the invention, there are shown in the accompanying drawings forms thereof which are at present preferred, since the same have been found in practice to give satisfactory and reliable results, although it is to be understood that the various instrumentalities of which the invention consists can be variously arranged and organized and that the invention is not limited to the precise arrangement and organization of the instrumentalities as herein shown and described.

In the accompanying drawings, in which like reference characters indicate like parts throughout,

Figure 1 represents a cross-sectional view on an enlarged scale of one embodiment of the present invention, parts being broken away better to reveal the construction thereof.

Figure 2 represents a cross-sectional view similar to that of Figure 1, but showing the relationship of the elements after the coupler has been attached to a fitting 61.

Figure 3 represents a perspective view of the embodiment shown in Figures 1 and 2.

Figure 4 represents a cross-sectional view of the coupler shown in Figures 1, 2 and 3 as it appears when partially disassembled; the units being arranged in exploded position and being designated as Figures 4a, 4b, 4c, and 4d.

Figure 5 represents a perspective composite view of the coupler shown in Figures 1 to 4 as it appears when fully disassembled; the units 4a, 4b, 4c, and 4d of Figure 4 being further disassembled into their respective parts and being designated as Figures 5a, 5b, 5c, and 5d respectively.

In one embodiment of the present invention, a main body housing or shell 20 is provided of

generally tubular formation having a reduced opening 21 in the forward end thereof. Said housing 20 is formed with an internal, generally cylindrical bore 22 in the forward portion thereof and of a generally cylindrical bore 23 in the rear portion thereof. The bore 23 is of slightly larger diameter than the bore 22; for example, the bore 22 may be made with a diameter of $\frac{1}{2}$ " while the bore 23 is made with a diameter of $\frac{17}{32}$ ".

A generally flat annular shoulder 24 is formed inside the housing 20 and serves to separate the bores 22 and 23.

The housing 20 may be internally threaded as at 25 in the rearmost portion thereof.

A knurled area 26 may be provided about the outer surface of said housing 20 to give a gripping surface thereon.

I prefer to give a slight forward taper to the outer surface of said housing 20 at the forward portion thereof as at 27.

A generally cylindrical sealing plunger 28 having an axial opening 29 therein and having a generally concave, spherical sealing surface 30 at the outer or forward end thereof, is provided within said housing 20. The rearmost or inner end of said plunger 28 is slightly radially outwardly enlarged as at 31. Said surface 30 (instead of being spherical) may be of any other suitable shape to correspond with the shape of the sealing surface 63 of a fitting 61 to be hereinafter described.

A washer 32 having a central opening 33 which is slightly larger than the outside diameter of the smaller cylindrical outer surface 34 of said plunger 28 (but smaller than the outside diameter of the enlarged portion 31 of said plunger 28) is slidably fitted about said outer surface 34 and extends radially outwardly therefrom beyond said enlarged portion 31. I prefer to construct said washer 32 with a generally rectangular cross section to provide generally flat front and rear surfaces thereon.

Said washer 32 extends radially outwardly into the larger cylindrical bore 23 of said housing 20 while the smaller-diaetered portion 34 of said plunger 28 extends into the smaller-diaetered cylindrical bore 22 of said shell 10 with the concave sealing surface 30 thereof terminating somewhat short of the forward opening 21 in said housing 20. The outer periphery of the forward face 35 of said washer 32 is adapted to rest on the annular shoulder 24 of said housing 20 when the device is in a generally non-operating position.

A plurality, preferably three, of nipple-grip-

ing jaw members 36, each curved to form approximately one-third of the circumference, surround the portion 34 of said plunger 28 and extend forwardly beyond the forward end thereof to a suitable extent and terminate in the inwardly-extending, nipple-gripping fingers 37 having the inclined, outer camming surfaces 2; said outer camming surfaces 38 being adapted to ride upon and to be actuated by the inclined inner annular camming surface 39 at the outward end 40 of said housing 20.

Slidably disposed within the cylindrical bore 23 and directly beyond said washer 32, is a cup-shaped cylinder 41 having the cylindrical opening or bore 42; said opening 42 having a diameter slightly greater than that of the enlarged rearmost portion 31 of said plunger 28 so that said rearmost portion 31 may reciprocate within said cylindrical opening 42.

The back-wall 43 of said cylinder 41 is formed with a somewhat smaller outside diameter than that of the main portion 44 thereof. An axial opening 45 passes through said back-wall 43 and communicates with the cylindrical opening 42 in said cylinder 41.

A cup-shaped leather or suitable composition washer 46 is disposed within said cylindrical opening 42 directly beyond said enlarged portion 31 of said plunger 28 to form a fluid-tight, piston-like seal between the enlarged portion 31 and the cylindrical bore 42. A central opening 47 is provided in said washer 46. A relatively thin, metallic, cup-shaped washer or spreader member 48 having a central opening 49 may also be provided within the cup-shaped washer 46 in order to keep it spread open and in order also to act as a seat for a helical compression spring 50 which is interposed between said washer 46 and the back-wall 43 of said cylinder 41. The more or less cylindrical or flange-like portion 71 of the washer 48 is preferably of an axial extent as great or slightly greater than the axial extent of the leather or composition washer 46 so that the free edge of the metallic washer 48 will strike the juxtaposed metallic part of the coupler (upon an extreme compression of the corresponding spring 59) before the free edge of the washer 46 strikes, thereby protecting the latter.

Thus, as shown in Figure 1, the spring 50 normally tends to urge the portion 31 forwardly within the opening 42 and thereby to maintain the sealing plunger 28 in its forwardmost position.

A plug member 51 having the externally-threaded tubular portion 52 is screwed into the threaded portion 25 of said housing 20 and forms a fluid-tight seal therewith, as shown in Figures 1 and 2. The protruding portion 73 of said plug member 51 may be formed with a pair of flattened sides 74 about the otherwise-cylindrical outer periphery thereof. Instead of providing the sides 74, I may make the outer surface of the protruding portion 73 polygonal; as for example hexagonal.

The tubular portion 52 has the inner cylindrical bore 53 which is slightly greater than the reduced back-wall 43 of said cylinder 41 so that said reduced back-wall 43 may be slidably reciprocated within said bore 53.

A generally cup-shaped leather or suitable composition washer 54 having the central opening 66 is disposed within said bore 53 directly behind said reduced back-wall 43 so as to form a fluid-tight seal between said wall 43 and said bore 53. A thin, metallic, cup-shaped washer

or spreader member 55 having a central opening 67 may be inserted within the washer 54 in order to keep it spread open and in order to act as a better seat for a helical compression spring 56 which is interposed between said washer 54 and the central wall 57 within said plug member 51. The cylindrical portion 72 of said washer 55 is preferably of a slightly greater axial extent than the axial extent of the leather cup-washer 54 (as described previously with respect to the washer 48). The spring 56 normally tends to urge the cup-shaped cylinder 41 to its forwardmost position within said housing 20 in which said washer 32 contacts the annular shoulder 24, and in which the nipple-gripping fingers 37 of the jaws 36 are maintained in their closed or gripping position.

An opening 58 is provided within the central wall 57 of said plug member 51 and forms a communicating passageway between the inner cylindrical bore 53 thereof and an outer cylindrical bore 59 formed in said plug member 51. The outermost portion of said outer bore 59 is internally threaded as at 60 whereby said plug member 51 may be screw-threadedly engaged to any suitable hose terminal or conduit 68 to which the coupler of the present invention is to be attached, as shown in Figure 2.

The coupler of the present invention is adapted to be connected to a fitting 61, as shown in Figure 2, of a form now well-known and in common use, and having a head portion 62 with a sealing surface 63 which may be spherical or any other suitable shape and having an undercut shoulder 64 which is adapted to be engaged by the fingers 37 of the jaw members 36, when said jaw fingers are contracted in a radially-inward direction by the action of the camming surface 39 upon the camming surfaces 38 of said jaw members 36.

Said fitting 61 also contains an opening 65 passing therethrough and communicating (when said coupler and said fitting are operatively engaged, as shown in Figure 2) with the openings 33, 47, 49, 42, 45, 66, 67, 53, 58 and 59 and with a conduit 68 or other fluid line connected to the plug member 51.

The fitting 61 also contains the check ball 69 and spring 70 in the usual manner.

The operation of the coupler constituting the present invention will now be described. As hereinbefore stated, when said coupler is not in use, the sealing plunger 28 is maintained in its advanced position by the spring 50 and the jaw members 36 are maintained in their advanced and contracted position by the spring 56. When said coupler is connected to said fitting 61, as shown in Figure 2, the act of forcing said coupler over the rounded head portion 62 of said fitting 61 first moves the fingers 37 of the jaw members 36 backwardly and radially outwardly against the spring 56 to permit the entry of said head portion 62 within said fingers 37. As the fitting 61 penetrates further within the forward opening 21 of the housing 20, the head portion 62 contacts the concave sealing surface 30 and forces said sealing plunger 28 inwardly against the spring 50.

When the head portion 62 has penetrated sufficiently far, the fingers 37 of the jaw members 36 are again forced forwardly and radially inwardly (by said spring 56) to enclose the undercut shoulder 64 of the head portion 62 and thereby to exert a gripping action preventing the involuntary dislodgment of said coupler from said

fitting 61. However, due to the fact, that said spring 56 is relatively weak, the coupler may be readily disconnected from said fitting 61, if desired, by merely pulling or tilting said coupler, sufficiently to spread the jaw members 36 to permit one or two of said jaw members 36 to ride over said head and to uncouple therefrom.

Thus, when the coupler has been seated fully upon said fitting 61, the gripping jaw members 36 are in an advanced position encircling the undercut shoulder 64 of said fitting 61 while the sealing plunger 28 is in a retracted position in which it is forced against the head portion 62 of the fitting 61 by the action of the spring 59, as shown in Figure 2.

When fluid (as for example lubricating grease) under pressure is introduced from said conduit 68 into the coupler, the pressure of the fluid acting upon the back-wall 43 of the cup-shaped cylinder 41 forces said jaw members 36 forward (with a very much greater force than is exerted by said spring 56) and causes the fingers 37 to grip the undercut shoulder 64 of the fitting 61 with a high degree of pressure and thereby to hold said coupler upon said fitting 61 firmly and irremovably.

The pressure of the fluid acting upon the enlarged portion 31 of the sealing plunger 28 (with a very much higher pressure than that exerted by the spring 50) forces said sealing plunger 28 forward and causes the sealing surface 30 to be held in fluid-tight sealing relationship with the sealing surface 63 of said fitting 61. The component elements of the coupler are so proportioned that the area of the back-wall 43 of the cylinder 41 is substantially greater than the area of the face of the enlarged portion 31 so that the hydraulic force tending to press the sealing surface 30 of the plunger 28 into sealing contact with the head 62 of the fitting 61 is less than the force transmitted to the gripping jaw members 36. The area of the face of the enlarged portion 31 is greater than the area of the head portion 62 which is exposed to the grease so that the force tending to press the sealing end 30 and the plunger 28 into sealing contact with the head 62 of the fitting 61 is substantially greater than the hydraulic force tending to separate the plunger from the nipple head.

The grease then passes through the openings 59, 58, 53, 67, 66, 45, 42, 49, 47, 33 and 65 to the bearing or other point to be lubricated. As long as the grease is passing through said openings under pressure, the coupler and the fitting 61 are held in fluid-tight and irremovable relationship. When the pressure is cut off, the jaws 36 and the sealing plunger 28 are held in their respective forward positions only by their respective springs so that when the period of lubrication has ended the fitting can readily be removed.

If desired, a check valve of any conventional type (not shown) may be provided to prevent the free return of fluid into the conduit 68 rearwardly of the coupler. Such a check valve may be placed for example with the bore 59 of the plug member 51.

The springs 50 and 56 may be suitably proportioned. They may be equal or unequal in strength. Thus, for instance, the spring 56 may be stronger than the spring 50 so that the compression of the spring 50 alone will not, in and of itself, cause a compression of the spring 56 or will cause only a lesser compression of the spring 56.

By providing the cup-washer 54, the washer 75

55, and the spring 56 within the bore 53 of the plug member 51, it is possible to provide a construction in which a fluid-tight seal is maintained between said plug member 51 and said housing 20 without the necessity for providing a gasket between the plug member and the housing (as would be required if said cup-washer 54, washer 55 and spring 56 were placed within the bore 23 of the housing 20 and the spring 56 merely bottomed against the plug member 51).

This feature has been found to be particularly advantageous since it simplifies the construction and minimizes the possibility of leakage of grease between the plug member and the housing.

15 As shown in Figure 4, it is possible to partially disassemble the coupler of the present invention into several more or less integral units. Thus, by unscrewing the plug 51 from the main housing 20, the unit designated, in Figure 4, as Figure 4d may be removed. The unit shown in Figure 4d includes the plug member 51, the spring 56, the spreader member 55 and the washer 54; the spring 56, the spreader member 55 and the washer 54 being retained within the inner bore 53 of the plug member 51 by the relatively close fit of said washer 54 within said bore 53.

After the unit shown in Figure 4d has been removed, the unit designated, in Figure 4, as Figure 4c may be similarly removed. The unit shown in Figure 4c includes the cup-shaped piston 41, the spring 50, the washer 46 and the spreader member 48; the spring 50, the washer 46 and the spreader member 48 being retained within the cylindrical bore 42 of said piston 41 by the relatively tight fit between said washer 46 and said bore 42.

After the unit shown in Figure 4c has been removed, the unit designated, in Figure 4, as Figure 4b may be removed. This unit includes the sealing plunger 28, the washer 32, and the three jaw members 36.

After the units designated as Figures 4d, 4c, and 4b, in Figure 4, have been removed, the shell or housing 20 which is designated, in Figure 4, as Figure 4a is left.

The units designated as Figures 4d, 4c, and 4b, in Figure 4, may then be further disassembled as shown in the composite view of Figure 5.

Thus, in Figure 5, Figure 5d shows the unit illustrated in Figure 4d after it is fully disassembled (by removing the washer 54 from the inner bore 53 of the plug member 51).

Figure 5c similarly shows the unit illustrated in Figure 4c after it has been fully disassembled (by removing the washer 46 from the bore 42 in the piston 41).

Figure 5b shows the unit illustrated in Figure 4b after it has been fully disassembled (by removing the jaw members 36 and by slipping the washer 32 off the sealing plunger 28).

Figure 5a is a perspective view of the shell or housing 20 which is designated as Figure 4a in Figure 4.

The present invention may be embodied in other specific forms without departing from the spirit or essential attributes thereof, and it is therefore desired that the present embodiment be considered in all respects as illustrative and not restrictive, reference being had to the appended claims rather than to the foregoing description to indicate the scope of the invention.

Having thus described the invention, what is hereby claimed as new and desired to be secured by Letters Patent, is:

1. A multi-jawed chuck-type hydraulic snap-

1. A coupler for use with headed fluid-receiving nipples, including a generally tubular housing shell having an apertured tapered forward end, said forward end having a generally annular inclined inner camming surface, said housing shell having a generally cylindrical front bore, a generally cylindrical larger-diametered rear bore and a generally annular shoulder separating said front and rear bores, an apertured plug member fitted within the rear end of said housing shell having a generally cylindrical bore in the inner portion thereof, an axially-apertured cylindrical sealing plunger fitted within said front bore and extending rearwardly into said rear bore and having an enlarged cylindrical rear portion, an annular ring slidably fitted about the main body of said sealing plunger and slidably disposed within said rear bore intermediate said annular shoulder and the enlarged rear portion of said sealing plunger, a plurality of independent gripping jaws circumferentially disposed within said front bore and about said sealing plunger having their rear ends abutting said annular ring and having inturned gripping jaws in operative juxtaposition to the inner camming surface of said housing shell, a generally cup-like cylinder slidably mounted within said rear bore behind said annular ring having a cylindrical inner bore and having a reduced-diameter apertured rear wall, the enlarged rear portion of said sealing plunger being slidably disposed within the cylindrical bore of said cup-like cylinder and being held therewithin by said annular ring, a spring disposed within the bore of said cup-like cylinder and urging said sealing plunger forwardly, the reduced-diameter rear wall of said slidably-mounted cup-like cylinder being slidably disposed within the cylindrical bore of said plug member and a spring disposed within said last-mentioned bore urging said cup-like cylinder, said annular ring and said gripping jaws forwardly within said housing shell.
2. A multi-jawed chuck-type hydraulic snap-on coupler for use with headed fluid-receiving nipples, including a generally tubular housing shell having an apertured tapered forward end, said forward end having a generally annular inclined inner camming surface, said housing shell hav-
- 5 ing a generally cylindrical front bore, a generally cylindrical larger-diametered rear bore and a generally annular shoulder separating said front and rear bores, an apertured plug member fitted within the rear end of said housing shell having a generally cylindrical bore in the inner portion thereof, an axially-apertured cylindrical sealing plunger fitted within said front bore and extending rearwardly into said rear bore and having an enlarged cylindrical rear portion, an annular ring slidably fitted about the main body of said sealing plunger and slidably disposed within said rear bore intermediate said annular shoulder and the enlarged rear portion of said sealing plunger, a plurality of independent gripping jaws circumferentially disposed within said front bore and about said sealing plunger having their rear ends abutting said annular ring and having inturned gripping jaws in operative juxtaposition to the inner camming surface of said housing shell, a generally cup-like cylinder slidably mounted within said rear bore behind said annular ring having a cylindrical inner bore and having a reduced-diameter apertured rear wall, the enlarged rear portion of said sealing plunger being slidably disposed within the cylindrical bore of said cup-like cylinder and being held therewithin by said annular ring, a cup-like axially-apertured sealing member slidably disposed within said bore behind the rear portion of said plunger, a cup-like, axially-apertured metallic spreader member within said cup-like sealing member, a spring disposed within the bore of said cup-like cylinder and seated 10 within said spreader member and urging said sealing plunger forwardly, the reduced-diameter rear wall of said slidably-mounted cup-like cylinder being slidably disposed within the cylindrical bore of said plug member, a cup-like 15 axially-apertured sealing member slidably disposed within said last-mentioned bore behind said rear wall, a cup-like, axially-apertured metallic spreader member within said sealing member and a spring disposed within said last-men-
- 20 25 30 35 40 45
20. having an enlarged cylindrical rear portion, an annular ring slidably fitted about the main body of said sealing plunger and slidably disposed within said rear bore intermediate said annular shoulder and the enlarged rear portion of said sealing plunger, a plurality of independent gripping jaws circumferentially disposed within said front bore and about said sealing plunger having their rear ends abutting said annular ring and having inturned gripping jaws in operative juxtaposition to the inner camming surface of said housing shell, a generally cup-like cylinder slidably mounted within said rear bore behind said annular ring having a cylindrical inner bore and having a reduced-diameter apertured rear wall, the enlarged rear portion of said sealing plunger being slidably disposed within the cylindrical bore of said cup-like cylinder and being held therewithin by said annular ring, a cup-like axially-apertured sealing member slidably disposed within said bore behind the rear portion of said plunger, a cup-like, axially-apertured metallic spreader member within said cup-like sealing member, a spring disposed within the bore of said cup-like cylinder and seated within said spreader member and urging said sealing plunger forwardly, the reduced-diameter rear wall of said slidably-mounted cup-like cylinder being slidably disposed within the cylindrical bore of said plug member, a cup-like axially-apertured sealing member slidably disposed within said last-mentioned bore behind said rear wall, a cup-like, axially-apertured metallic spreader member within said sealing member and a spring disposed within said last-mentioned bore and seated within said last-mentioned spreader member urging said cup-like cylinder, said annular ring and said gripping jaws forwardly within said housing shell.

EDWIN P. SUNDHOLM.
